UNITED STATES PATENT OFFICE.

J AMORY SMITH, OF ELLSWORTH, KANSAS.

COMBINED NECKTIE AND COLLAR FASTENER.

1,299,801.

Specification of Letters Patent.

Patented Apr. 8, 1919.

Application filed January 18, 1917. Serial No. 143,041.

To all whom it may concern:

Be it known that I, J AMORY SMITH, a citizen of the United States, residing at Ellsworth, in the county of Ellsworth and State of Kansas, have invented a certain new and useful Improvement in Combined Necktie and Collar Fasteners, of which the following is a specification.

My invention relates to improvements in combined necktie and collar fasteners.

The object of my invention is to provide a novel necktie and collar fastener which is cheap to manufacture, attractive in appearance, which may be substituted for the usual collar button used to attach a collar to the rear portion of the collar band of a shirt, which may be easily attached to the collar and to the shirt, which is adapted to receive the necktie and to permit of its being easily slid longitudinally to a desired position, and which will permit of the ready attachment or detachment of the collar.

The novel features of my invention are hereinafter fully described and claimed.

In the accompanying drawing which illustrates the preferred embodiment of my invention,

Figure 1 is a perspective view, enlarged, of my improved necktie and collar fastener. Fig. 2 is an enlarged vertical sectional view of the same, shown attached to a shirt and collar, portions only of the shirt and collar being shown.

Fig. 3 is an enlarged edge elevation of my improved fastener.

Fig. 4 is an enlarged rear elevation of the same.

Similar reference characters designate similar parts in the different views.

My improved fastener is preferably made of sheet metal bent at right angles to its thickness into a U-shaped portion, one of the arms, 1, of which is adapted to be inserted under the rear portion 2 of the collar band of a shirt 3, Fig. 2. The other arm 4 of said U-shaped portion is connected by a transverse portion 5 to the adjacent arm 6 of an inverted U-shaped portion having a rear downwardly extending arm 7. The inverted U-shaped portion 6-7 is adapted to be mounted between the folds of an ordinary turn-down collar 8, as shown in Fig. 2, and is also adapted to receive between its arms a necktie 9 which may be longitudinally slid between said arms to any desired position.

The transverse portion 5 is adapted to be extended through the rear button-hole 10 of the collar 8.

The arm 6 is provided, preferably, at opposite sides respectively of the transverse portion 5 with two projections 11 which extend below the portion 5 and are also adapted to extend below the button-hole 10, for the purpose of more securely holding the fastener securely attached to the collar 8 to which the fastener is ordinarily secured when the collar is in use and when it has been laid aside for the night.

In applying the fastener to a collar, the U-shaped portion 1-4 is inserted from the rear side through the button-hole 10 by first slipping the arm 1 thereof upwardly through the button-hole 10, and then forcing the arm 4 downwardly through the button-hole until the projections 11 are disposed below the button-hole, as shown in Fig. 2. The tie 9 may then be extended between the arms 6 and 7 and the arm 1 then slipped under the collar band 2 of the shirt, as shown in Fig. 2. The ends of the collar 8 may then be attached in the usual manner to the front collar button. The tie 9 may now be drawn longitudinally to any desired position. As shown in the drawing, the arm 7 of the inverted U-shaped portion extends below the lower ends of the projections 11 and is parallel with the arm 6. By having the arm 7 extending below the lower ends of the projections 11, the tie may be easily slipped upwardly into position between the arms without liability of catching on the ends of the arms, although the latter are close together and parallel with each other. By having the arms 6 close together and parallel, bulging of the collar is avoided and the tie is held from slipping downwardly.

When the collar 8 is removed from the shirt after the ends have been unbuttoned, it is but necessary to slip the arm 1 downwardly out of connection with the collar band 2. The fastener will then be securely retained in the rear button hole of the collar until it is desirable to remove it for the purpose of having the collar laundered. By having the two projections 11 at opposite sides respectively of the transverse portion 5, the fastener is not liable to lateral tipping when the tie is drawn lengthwise between the arms 6 and 7.

I do not limit my invention to the struc-

ture shown and described, as modifications within the scope of the appended claims, may be made without departing from the spirit of my invention.

5 What I claim is:—

1. A combined necktie and collar fastener comprising two U-shaped portions, one of which is inverted, one of the arms of the inverted portion being bifurcated, one of the 10 arms of the other U-shaped portion having a transverse portion connected to said bifurcated arm between and at the upper ends of said bifurcations.
2. A combined necktie and collar fastener 15 comprising two U-shaped portions, one of which is inverted, the arms of each portion being parallel with each other, one of the arms of the inverted portion being bifurcated, the other arm of the inverted portion extending below the lower ends of said bi- 20

furcations, and one of the arms of the other U-shaped portion having a transverse portion connected to said bifurcated arm between and at the upper ends of said bifurcations.

3. A combined necktie and collar fastener comprising two U-shaped portions, one of which is inverted, one of the arms of the inverted portion having a downwardly extending projection, the other arm of the inverted portion extending below the lower end of said projection, and one of the arms of the other U-shaped portion having a transverse portion connected to the arm having said projection at the upper end of said projection. 25

In testimony whereof I have signed my name to this specification.

J AMORY SMITH.
